(57) **CLAIM**

The ornamental design for a camera for a baby monitor, as shown and described.

DESCRIPTION

FIG. 1 is a top front perspective view of a camera for a baby monitor, according to my new design.

FIG. 2 is a bottom rear perspective view thereof.

FIG. 3 is a right side elevational view thereof;

FIG. 4 is a front elevational view thereof;

FIG. 5 is a left side elevational view thereof;

FIG. 6 is a rear elevational view thereof;

FIG. 7 is a top plan view thereof; and,

FIG. 8 is a bottom plan view thereof.

This design is directed to a camera for a baby monitor. The broken line showing of parts of the drawings is included for the purpose of illustrating use and environment and forms no part of the claimed design.
